2,174,914

EXPLOSIVE AND METHOD FOR ITS PRODUCTION

Willard de C. Crater, Newark, Del., assignor to
Hercules Powder Company, Wilmington, Del., a
corporation of Delaware

No Drawing. Original application April 26, 1934,
Serial No. 721,545. Divided and this application
May 12, 1937, Serial No. 142,321

6 Claims. (CL 52—11)

This invention relates to a new type of explosive and to methods for its production.

It has been known to attempt the nitration of various crude cellulosic materials, as, for example, wood pulps, to obtain nitrocellulose. In order to render the nitrocellulose so obtained utilizable in smokeless powders, etc. it was essential to obtain a high degree of nitration (around 13%), and the resultant product was always too unstable for satisfactory use.

Now in accordance with this invention it has been found possible to produce nitrated materials from crude cellulosic materials such as, for example, balsa wood, bagasse, oat hulls, wood flour, etc., which can be successfully formulated into high explosives. The nitrated materials in accordance with this invention will contain only from 9—11.5% nitrogen, and will accordingly be sufficiently stable for satisfactory use. In formulating an explosive in accordance with this invention, the nitrated material as, for example, nitrated balsa, nitrated bagasse, nitrated oat hulls, nitrated wood flour, etc. will be impregnated with what may be termed an explosive oxidant, as, for example, ammonium nitrate, ammonium perchlorate, potassium chlorate, etc. The term "explosive oxidant" is meant to designate those materials, well known in the explosives art, which, while not themselves explosive in the ordinary meaning of the word, are capable of forming a detonatable mixture when combined with organic materials, and which when present in an explosive actually take part in the explosion. The explosive in accordance with this invention will accordingly comprise a nitrated cellulosic material impregnated with an explosive oxidant.

The nitrated cellulosic material in accordance with this invention may be produced by nitration of the comminuted raw material, as, for example, balsa pulp, bagasse pulp, oat hulls, wood flour, etc. with mixed nitric and sulphuric acids in the manner well known to the art, for example, as flaked starch is nitrated. (See U. S. Pat. 1,908,857 to George M. Norman.) The mixed acids are chosen to give a product of from about 9% to about 11.5% nitrogen.

The nitrated cellulosic material will be found to retain essentially the same physical appearance and properties as the raw product from which it was made, and will accordingly be highly absorptive. The impregnation of this nitrated material with an explosive oxidant can be accomplished in various ways.

Thus, in accordance with this invention, the ex-

plosive oxidant may be dissolved in water to form a concentrated solution, the nitrated cellulosic material stirred into this solution until the liquid has been all absorbed, and the resultant product dried until it becomes crisp and free flowing. For example, 20 grams of ammonium nitrate may be dissolved in 3 to 4 cc. of water at 75—80° C., and 5 grams of dry nitrated balsa pulp are then stirred into the solution. The product is then dried to 105° F. until it becomes crisp and free-flowing. The explosive so produced may be detonated by a #6 electric blasting cap, and has a weight strength of about 63.3%.

In order to avoid the necessity of drying the nitrated cellulosic material before the impregnation (which presents some fire hazard owing to the dusty nature of the dry material), the wet nitrated material as taken from the final stabilizing wash or boil may be mixed with the finely ground explosive oxidant, the residual water acting as a solvent for the salts and effecting impregnation. The product may then be dried as described above. For example, wet nitrated balsa pulp may be thoroughly mixed with four times its dry weight of ammonium nitrate, or of equal parts ammonium and sodium nitrates, and then dried at 105° F. until crisp and free flowing. The use of ammonium nitrate alone gives an explosive having a 100 lb. count of 509 and a weight strength of about 65.3%. The explosive containing sodium nitrate has a 100 lb. count of 498 and a weight strength of about 28.3%.

By using this method water-insoluble materials may also be incorporated. For example, an explosive may be made from wet nitrated balsa having the following compositions and properties:

	Percent
Nitrated balsa (dry weight)	10 40
Ammonium nitrate	10
Sodium nitrate	65
Charcoal	8
Sulfur	7 45
Count per 100 lbs	440
Weight strength	9.5

Impregnation of the nitrated cellulosic material can also be effected by treating the pulp with a solution of ammonium nitrate in liquid ammonia (Diver's liquid), or by a mixture of ammonium nitrate and hydrated magnesium nitrate in accordance with the method shown in U. S. Pat. 1,671,792 to B. I. Stoops. These methods

avoid the necessity of drying the impregnated material at an elevated temperature.

If the nitrated cellulosic material is sufficiently absorptive and does not contain more than about 10% nitrogen, the nitrated impregnated material produced as described above may be further impregnated with nitroglycerin to give a stronger explosive. Thus an explosive may be formulated containing:

	Per cent
Nitrated balsa pulp	20
Ammonium nitrate	70
Nitroglycerin	10

16 In addition to the nitrated crude cellulosic materials, as balsa wood, bagasse, oat hulls, already referred to, nitrated starch flakes and nitrocellulose can also be impregnated in accordance with this invention to form a powerful explosive. Their natural absorbency, however, is not as great as that of the crude cellulosic materials.

20 However, since these carbonaceous materials (starch and cotton) can be obtained in a substantially pure form, they may be nitrated to give products having more nitrogen than 11.5% without becoming unstable.

25 Thus, for example, 75 g. of ammonium nitrate may be dissolved at 75-80° C. in a minimum of water, and 25 g. of dry nitrated starch flakes, produced, for example, by the method described in U. S. Pat. 1,908,857 to Norman, may be stirred into the solution. The material, when dried at about 105° F., is granular and free flowing and 30 has a weight strength of 70.3%.

35 Also, wet nitrostarch flakes may be treated with the finely ground explosive oxidant in the manner heretofore described. By this method an explosive of the following composition was produced:

	Per cent
Nitrostarch flakes (dry weight)	15
Ammonium nitrate	25
Sodium nitrate	56
Balsa pulp	4

50 The balsa pulp is added to increase the absorptiveness of the mixture and so to aid impregnation.

55 A solution of 30 g. of ammonium nitrate in a minimum of water may be used to impregnate 20 g. of dry nitrocotton (13%N). The dried product has a weight strength of 70.9%.

From the various examples given above it will have been seen that various common ingredients of explosives other than explosive oxidants, for example, sodium nitrate, charcoal, sulfur, unni-60 trated wood pulps, may be used in conjunction with the explosive oxidant in producing explosives in accordance with this invention.

While ammonium nitrate has been indicated as the explosive oxidant used in the examples given, other explosive oxidants, as for example, ammonium perchlorate, etc. may be used to replace the ammonium nitrate either in whole or in part. For example, explosives in accordance with this

invention may have the following compositions:

	Per cent
Nitrated balsa	20
Ammonium perchlorate	80

5 By way of recapitulation the following table shows, solely as examples, various types of explosives produced in accordance with this invention:

Material	Per cent	Per cent NH ₄ NO ₃	Dens.	Detonates with #8 E.B. cap	Weight strength per cent	10
Nitrated balsa	20	80	.33	Yes	64.24	12
Nitrated bagasse	20	74	.35	Yes	68.78	13
Nitrated oat hulls	33 1/3	63 2/3	.22	Yes	14.16	14
Nitrated wood flour	20	80	.41	Yes	71.33	15
Nitrated wood flour flakes	25	75	.46	Yes	70.33	16
Nitrated starch	20	80	.44	Yes	70.90	17

The explosives in accordance with this invention have many desirable properties. They are powerful, relatively insensitive to shock yet easily detonated by proper means, inexpensive, and (if they do not contain nitroglycerin or the like) non-freezing and non-headache-producing. 20

25 Explosives in accordance with this invention will also be found to be free flowing and accordingly may be readily cartridgeed, or, if desired, may be poured directly into bore holes.

This application is a division of application 30 Serial No. 721,545 filed by me April 20, 1934 for improvement in Explosive.

What I claim is:

1. Method of producing an explosive which includes treating an absorptive, nitrated, cellulosic material with a solution of an explosive oxidant in liquid, anhydrous ammonia. 35

2. Method of producing an explosive which includes treating an absorptive, nitrated, cellulosic material with a solution of an explosive 40 oxidant in liquid, anhydrous ammonia, and then evaporating the liquid ammonia.

3. Method of producing an explosive which includes treating nitrated balsa wood with a solution of an explosive oxidant in solution in liquid, anhydrous ammonia and then evaporating the liquid ammonia. 45

4. Method of producing an explosive which includes treating nitrated balsa wood with a solution of ammonium nitrate in liquid, anhydrous ammonia and then evaporating the liquid ammonia. 50

5. An explosive composition comprising about 8 parts by weight of charcoal, about 7 parts by weight of sulfur and about 10 parts by weight of nitrated balsa wood containing from about 9% to about 11.5% nitrogen and impregnated with about 10 parts by weight of ammonium nitrate and about 65 parts by weight of sodium nitrate. 55

6. An explosive composition comprising about 10 parts by weight of nitroglycerine and about 20 parts by weight of nitrated balsa wood containing from about 9% to about 11.5% nitrogen and impregnated with about 70 parts by weight of ammonium nitrate. 65

WILLARD DE C. CRATER.
